UNITED STATES PATENT OFFICE

HARRY BONAT, OF NEW YORK, N. Y.

HAIR WAVING ACCESSORY

Application filed November 24, 1930. Serial No. 497,639.

This invention relates to improvements in accessories for use in connection with the permanent waving of hair and more particularly to accessories for use in connection with the wrapping of hair around spools prior to the application of heat in the permanent waving of hair.

Heretofore when hair was to be wrapped around a spool preparatory to the application of heat, it has been customary to wrap the hair around the spool manually by turning the spool with both hands, first with one hand and then with the other. As a result of this turning, first with one hand and then with the other, considerable inconvenience in the wrapping of the hair around the spool resulted. It is almost impossible to wrap hair around a spool, turning the spool first with one hand and then with the other, without twisting the hair in such a manner as to prevent it from being wrapped evenly around the spool.

An object of the present invention is to provide means for assisting in wrapping hair evenly around a spool.

Another object of the invention is to provide means whereby unwrapping of the hair during the wrapping operation is prevented.

A still further object of the invention is to provide improved ratchet and pawl arrangements in connection with spools for preventing unwrapping of the hair.

According to the present invention, use is made of a device somewhat in the nature of a thimble for holding one end of the spool during the operation of wrapping the hair therearound while the other end of the spool is turned manually. This thimble may be a metallic member of any desired configuration so long as it is provided with an opening into which one end of the spool may fit. If desired, the thimble may be provided with a pawl for engagement with ratchet teeth on the end of the spool so that unwrapping of the hair is prevented. Furthermore, the invention consists in one instance of providing an improved ratchet and pawl arrangement in conjunction with the spool itself. This improved arrangement consists briefly of providing one end of the spool with a

hollowed-out portion into which a pin having a circumferential collar of larger diameter and provided with ratchet teeth may be inserted. Also insertable into the end of the hollowed-out portion of the spool is a ringlike member provided with radial teeth for engagement with the before-mentioned teeth. When this collar is secured in place within the end of the spool, it is possible to turn the pin in one direction only, since it is pressed against the collar by means of a spring. It follows from this that by firmly gripping the pin, the spool itself may be rotated in only one direction.

When the spool utilized in the waving of the hair is one employing this improved ratchet arrangement, the thimble of the invention may be somewhat modified; that is, a further opening is provided therein for the reception of the end of the pin.

In still another form of the invention, a ratchet arrangement similar to that previously described in connection with the spool may be built into the thimble, the movable collar of the arrangement being adapted to be engaged by a solid pin extending from one end of the spool.

In still another form of the invention, use may be made of the improved ratchet arrangement in connection with the spool, and, in addition thereto, an enlarged handle may be provided at the end of the elongated pin, which handle may be held firmly in one hand while the spool is rotated. The thimble may be dispensed with when this type of construction is used.

Other features, objects and advantages of the invention will become apparent by reference to the following detailed description taken in connection with the accompanying drawing wherein

Figure 1 is a perspective view of the use of the invention;

Fig. 2 is a view partially in section of the improved ratchet mechanism embodied in a spool together with a thimble for aiding in the wrapping of hair around the spool;

Fig. 3 is a view of the parts of the improved ratchet member before assembly;

Fig. 4 is a section taken on the lines 4—4 of Fig. 2;

Fig. 5 is a view in section of the modification of the invention wherein a thimble is provided with the improved ratchet mechanism;

Fig. 6 is a view in section of the simplest form of thimble used in connection with the invention; and

Fig. 7 is a view partially in section of an improved spool provided with the ratchet mechanism of the invention, together with a handle for aiding in the wrapping operation.

Referring now to the drawing and particularly to Figs. 2, 3 and 4, 10 indicates a spool around which hair may be wrapped prior to subjecting the same to heat for waving the hair. This spool 10 is provided with the usual hair-retaining member 11 and enlargement 12 at one end for permitting manual rotation thereof. The opposite end of the spool, however, is hollowed out as shown in Fig. 3 and also, if desired, provided with radial teeth 13. Insertable into this hollowed-out portion of spool 10 is a pinlike member 14 having an enlarged portion 15 provided with radial teeth 16. One end of the pin 14 may be made of square shape or any other desired configuration as shown at 17. Also insertable into the end of spool 10 is a collar 18, likewise provided with radial teeth 19 of shape and size to engage the teeth 16.

The parts being shown in Fig. 3 before assembly, their relative position after assembly is shown in Fig. 2. The member 14 is first introduced into the end of spool 10 with a coil spring 20 therearound. As shown in Fig. 2, the opening in the end of spool 10 has a portion of reduced diameter of size sufficient to receive the pin 14 only, thereby providing a shoulder against which one end of spring 20 may press, the other end being pressed against enlargement 15. When the pin 14 has been properly introduced into the end of spool 10, the collar 18 is then likewise positioned therein and secured in place by means of a set screw 21 or any other suitable arrangement. With the collar locked in position, it is possible to rotate the pin 14 in one direction only, since the teeth 16 and 19 are held in engagement by means of spring 20. Furthermore, if the end 17 of the pin be held against movement, it is then possible to rotate the spool 10 in one direction only, since in this position the movable member is the collar 18 and not the enlargement 15.

When this type of improved spool with ratchet arrangement is used, it is advantageous to use the type of thimble of the invention shown in Fig. 2 in conjunction therewith. This thimble, which is of prime importance in the wrapping of hair around the spool, consists in its simplest form of a metallic rod 25 provided at one end with an

opening circular in form so that annular walls 26 are thereby formed. Immediately adjacent to this opening is a further opening 27 of configuration corresponding to that of the end 17 of the pin forming a part of the spool.

The operation of the mechanism just described is substantially as follows. Hair is given an initial wrap around spool 10, being held in place by the latch. The end of the spool having the pin protruding therefrom is then introduced into the thimble 25, the portion 17 entering the opening 27. With the parts in this position, the hair is wrapped around the spool by rotating the enlargement 12 with one hand, holding the thimble 25 firmly in the other hand. Since the ratchet arrangement embodied in the spool permits rotation of the spool in one direction only, and, since the spool is locked within the thimble by means of the corresponding parts 27 and 17, it will be seen that only one hand actually accomplishes the turning of the spool during wrapping of the hair. By utilizing this thimble, the unevenness resulting from wrapping the hair by turning the spool first with one hand and then with the other is overcome. As soon as the hair has been wrapped almost completely around the spool, the thimble 25 is withdrawn from the end of the spool and the pin 17 introduced into slot 30 in a standard extending from one end of a protector, the component parts of which grip the hair. With the pin 17 in place in the slot 30, the completion of the wrapping operation is carried out, leaving the spool finally resting on the protector.

A modification of the invention is shown in Fig. 5, wherein the thimble 25a is provided with an opening similar to that in the end of spool 10, into which may be introduced a pin 34 having enlargement 35 provided with teeth 36; together with a collar 38 having teeth engaging teeth 36. This collar is held in place against movement by means of set screw 41 or any other desired arrangement. Instead of providing one end of pin 34 with a portion corresponding to part 17, the enlargement 35 is provided with an opening of shape to receive the end of pin 42 extending from spool 10. This end 42 is preferably square shaped or some other shape which permits locking of that part with an opening.

When the parts are in the arrangement illustrated, the wrapping of hair is accomplished in the same manner as before explained, the only difference being that the turning of ratchet members is accomplished in the thimble itself and not in the spool. When the hair is almost completely wrapped around the spool, the thimble is disengaged and the pin 42 introduced into the bottom of slot 30, which is rounded to permit rotation of the pin therein. As is customary in the construction of protectors, the standard hav-

ing slot 30 is provided with a pawl for engagement with teeth 13 on the end of spool 10.

The simplest form of thimble forming a part of the invention is shown in Fig. 6 wherein use is made of a metallic rod 50 provided with an opening in one end of such character as to form an annular wall 51. Into this opening may be introduced one end of a spool which may have ratchet teeth or not as the case may be, such teeth being indicated at 52. The member 50 may be provided with a pawl member 53 for engagement with teeth 52. This structure may be used with a spool having teeth as shown or with a spool not provided with teeth as occasion may demand. When teeth are provided the engagement between such teeth and the pawl prevents reverse movement of the spool during the wrapping of hair therearound.

A further modification of the invention is shown in Fig. 7 wherein the construction shown in Fig. 2 is duplicated with the addition of slight changes. Instead of terminating the pin with a square portion 17 as in Fig. 2, it is extended beyond this portion 17 into a rounded part 60 to which may be secured in any desired manner a knurled knob 61.

When this type of construction is used, it is not necessary to make use of a thimble, since the operator merely holds the knurled knob 61 in one hand, turning the spool 10 by means of enlargement 12 with the other. Since the pin having the knob 61 secured thereto is in effect immovable, it is possible to rotate the spool in one direction only so that unwrapping of the hair is prevented. When the hair is almost completely wrapped around the spool, the spool may be positioned on the protector as before, fitting the squared portion 17 into the slot 30 and then completing the wrapping operation.

It will be apparent from the foregoing, that the present invention in its parts provides new, simple, inexpensive and useful accessories which form essential parts in the preparation of hair for permanent waving. It is to be understood that the invention is capable of modification from the illustrated embodiments and that therefore any limitation imposed thereupon must be imposed in view of the appended claims.

Having described my invention, I claim:

1. A device of the character described comprising a substantially solid member having a hollowed-out portion in one end thereof for the reception of an end of a spool during the wrapping of hair therearound.

2. A device of the character described comprising a substantially cylindrical member having a hollowed-out portion forming an annular wall, said hollowed-out portion receiving an end of a spool during the wrapping of hair therearound.

3. A device of the character described comprising a member having a hollowed-out portion in one end thereof for the reception of an end of a spool, a pawl member within said hollowed-out portion engageable with ratchet teeth on said end of the spool.

4. The combination with a spool around which hair is to be wrapped of a thimble having a hollowed-out portion for the reception of one end of said spool and cooperating means within said opening and on said spool for preventing reverse turning of said spool while hair is being wrapped therearound.

5. The combination of a spool around which hair is to be wrapped, a pin extending from one end of said spool and rotatable in a single direction with respect thereto and a thimble having an opening for the reception of one end of said spool and having a further opening for the reception of said pin, said pin being held against rotation in the opening.

6. A device of the character described comprising a member having a hollowed-out portion for the reception of an end of a spool, said member being provided with an additional opening, a pin mounted in said additional opening for rotation in a single direction and provided with a recess for the reception and retention of a pin extending from one end of said spool.

7. A device of the character described comprising a member having a hollowed-out portion and with an additional opening, a pin rotatably mounted in said additional openings, a collar secured therein to prevent outward movement of the pin, matched ratchet teeth on the contacting surfaces of said pin and collar and means for forcing said teeth into engagement whereby said pin is rotatable in a single direction.

8. A device of the character described comprising a member having a hollowed-out portion and with an additional opening, a pin rotatably mounted in said additional opening, a collar secured therein to prevent outward movement of the pin, matched ratchet teeth on the contacting surfaces of said pin and collar and means for forcing said teeth into engagement whereby said pin is rotatable in a single direction, said pin being provided with a recess for the reception of the end of a pin passing through said collar.

9. A device of the character described comprising a spool, a pin extending from one end thereof and having a portion rotatably secured within said spool, ratchet teeth on said pin and ratchet teeth within said spool, and means for yieldingly forcing said teeth together to positively limit the rotation of the pin to a single direction.

10. A device of the character described comprising a spool, a pin extending from one end thereof and having a portion rotatably secured within said spool, ratchet teeth on said pin and ratchet teeth within said spool,

and means for yieldingly forcing said teeth together to positively limit the rotation of the pin to a single direction, and an enlargement on the extremity of said pin whereby

5 when said enlargement is gripped said spool is rotatable in a single direction with respect thereto.

11. A device of the character described comprising a spool having an opening within one end thereof, a pin rotatably mounted within said opening, a collar secured in said opening to restrain said pin from outward movement, matched ratchet teeth on the contacting surfaces of the pin and the collar, means for forcing said teeth into engagement to limit the relative rotation of said pin and spool to a single direction, and prolongation of said pin extending through said collar beyond the end of the spool.
12. A device of the character described comprising a spool having an opening within one end thereof, a pin rotatably mounted within said opening, a collar secured in said opening to restrain said pin from outward movement, matched ratchet teeth on the contacting surfaces of the pin and the collar, means for forcing said teeth into engagement to limit the relative rotation of said pin and spool to a single direction, and prolongation of said pin extending through said collar beyond the end of the spool, said prolongation being provided with an enlargement on the extremity thereof.

13. The combination of a spool having an opening within one end thereof, a pin rotatably mounted within said opening, a collar secured in said opening to restrain said pin from outward movement, matched ratchet teeth on the contacting surfaces of the pin and the collar, means for forcing said teeth into engagement to limit the relative rotation of said pin and spool to a single direction, and prolongation of said pin extending through said collar beyond the end of the spool, and a thimble having successive openings for the reception of said pin and the end of the spool.

14. The combination of a spool having an opening within one end thereof, a pin rotatably mounted within said opening, a collar secured in said opening to restrain said pin from outward movement, matched ratchet teeth on the contacting surfaces of the pin and the collar, means for forcing said teeth into engagement to limit the relative rotation of said pin and spool to a single direction, and a prolongation of said pin extending through said collar beyond the end of the spool, and a thimble having successive openings for the reception of said pin and the end of the spool, said pin being held against rotation in said thimble, whereby the spool is rotatable in a single direction with respect to the thimble.
